UNITED STATES PATENT OFFICE.

ALEXANDER McCAIN AND THOMAS CARLYLE GRIERSON, OF EVELETH, MINNESOTA.

ORE-CONVEYER.

SPECIFICATION forming part of Letters Patent No. 745,368, dated December 1, 1903.

Application filed August 2, 1902. Serial No. 118,163. (No model.)

To all whom it may concern:

Be it known that we, ALEXANDER McCAIN and THOMAS CARLYLE GRIERSON, citizens of the United States, residing at Eveleth, in the 5 county of St. Louis and State of Minnesota, have invented a new and useful Ore-Conveyer, of which the following is a specification.

This invention relates generally to ore-conveyers, and more particularly to a construction embodying an ore-conveyer and stock-piler.

The object of the invention is to convey the ore from the mine and stock or pile the same adjacent thereto during the winter months or 15 at a time when it is not convenient to move the same to the furnace.

Another object of the invention is to provide a construction embodying these characteristics which will be exceedingly easy to 20 manipulate and which will dispense with a considerable quantity of labor.

With these and certain other objects, as will appear hereinafter, the invention consists in the details of construction and also in the 25 novel combination and arrangement of the various parts, all of which will be fully set forth in the specification and pointed out in the claims.

In the drawings forming a part of this specification, Figure 1 is a side elevation of a combined conveyer and stock-piler constructed and arranged in accordance with my invention. Fig. 2 is a top plan view of the same. Fig. 3 is a detail perspective view of one of 30 the cars. Fig. 4 is a vertical sectional view of one of the cars, said view being broken away. Fig. 5 is a sectional view on the line 5 5 of Fig. 4 on an enlarged scale. Fig. 6 is a detail perspective view of the buffer, and 35 Fig. 7 is a detail side elevation showing the operation of the parts when the car comes in contact with the buffer. Fig. 8 is a diagrammatic view showing means for regulating the buffer. Fig. 9 is an enlarged detail view, 40 partly in section, showing a portion of Fig. 8.

In carrying out our invention we employ the usual construction of shaft-house frame A, carrying a sheave A' at its upper end, over which the cable A² passes, elevating the car 45 A³ for the purpose of discharging the ore or

other material into one of the dumping-cars forming a part of our improved construction of stock-piler.

B indicates the tower mounted upon wheels B', which travel upon the tracks B², arranged 55 at any desired distance from the shaft-house derrick or frame. The track and tower are both anchored in any suitable manner, so as to render the tower fixed or immovable after having once been adjusted at the proper point. 60

Track-cables C are fastened at one end to the shaft-house derrick or frame, pass over shafts C', carried at the upper end of the tower, and are connected at their lower ends to windlasses C², arranged adjacent to the 65 lower end of the tower B and by means of which the track-cables can be properly adjusted.

In the drawings we have shown two sets of track-cables, and there will of course be two sets of elevator-cars A³ and also two sets of 70 dumping-cars; but it will of course be understood that any desired number of cables and cars may be employed, according to the capacity of the mine and the amount of material to be handled. In the further description 75 of our invention, however, we shall only refer to one set of track-cables and one dumping-car, together with the operative mechanism connected to or operated upon the said car, it being understood, of course, that all 80 cars are of the same construction and the operating mechanism is the same in each case.

The dumping-car D travels upon the track-cables C, said car having grooved rollers D' arranged upon opposite sides thereof adjacent to the upper end and which travel upon the track-cable C, these rollers being arranged in strap-loops D², and directly beneath each roller D' is a similar guiding-roller D³. The car has a bottom D⁴, hinged at D⁵, 85 and adapted to drop downwardly, as indicated in Fig. 7, and this bottom carries the axles D⁶, having wheels D⁷, which travel upon the tracks arranged upon the shaft-house derrick or frame. The bottom D⁴ is normally 90 held closed by means of a spring-actuated catch-lever E, the lower portion of which is bifurcated, said lever being pivoted in the bracket E', attached to the end of the car, and the hooked ends E² are adapted to engage the 95 100

under side of the bottom of the car and hold the said bottom closed. Catch-lever E is normally held in this position through the medium of a spring E³, contained within a sleeve E⁴, connected to the end of the car and between the members of the lever, said spring bearing directly against the bar E⁵, which connects the said members of the lever and works in longitudinal slots E⁶, produced in the sleeve E³, as most clearly shown in Fig. 5. By this construction the lower hooked ends of the lever are normally held in engagement with the bottom of the car, and consequently the bottom of the car is kept closed.

15 The elevator-car A³ discharges the material into the dumping-car D, and the dumping-car then is moved outwardly upon the track-cables, the end carrying the lever being foremost, and these cars continue to move outwardly until the lever comes in contact with a buffer F, arranged at any desired point upon the track-cables, and when the upper end of the catch-lever E contacts with the said buffer the lower hooked ends of the lever are disengaged from the bottom of the car, and the said bottom will then drop by its own weight and will discharge its contents where it is desired to pile the stock. After the car has been dumped it is thrown back to its former position, ready to receive another load, and in being returned the hinged bottom is moved upwardly and closed, as hereinafter explained.

In order to move the car back and forth upon the track-cables, we employ a rope G, which is connected to the forward end of the car, passed around the sheave G', back over a sheave G², to a drum at the engine-house, then returned over a sheave G³ and connected to the rear side of the car, as shown at G⁴. Guide-pulleys G⁵ are arranged upon opposite sides of the car adjacent to the bottom of the same and between which the rope G travels, the said guide-pulleys being carried by the strap-loops or brackets G⁶. Thus it will be understood that by operating the ropes from the engine-house the dumping-car D will be caused to move backward and forward upon the track-cables.

50 As the car D approaches the shaft-house derrick the wheels D⁹ come in contact with a curved or inclined buffer-block H, by means of which the bottom is elevated and secured in its closed position as the car moves inwardly to receive the second charge.

The buffer F comprises an essentially open frame F', strengthened by suitable braces F², and guide-rollers F³ are arranged upon the opposite sides of the frame, carried in suitable loops or brackets F⁴. The track-cables C pass between these guide-rollers F³, and thus support the buffer upon the track-cables. A rope F⁵ passes from the forward end of the buffer over a sheave F⁶ and carries a weight F⁷ at its lower end, the purpose of said weight being to take up any slack which may be occasioned by the cars coming in contact with

the buffer F, and the purpose of this rope is to hold the buffer in its proper position. If desired, another rope F⁸ may be connected to the opposite end and may extend into the shaft-house and by means of which the buffer can be drawn in the opposite direction whenever desired.

To prevent the buffer running back after the car beyond the point at which it should rest, a perforated lug F⁹ is secured to the tower B, through which the rope passes. An adjustable stop F¹⁰ is secured on the rope below the lug. When the buffer is struck by a car, it will be driven backward a few feet, the weight F⁷ keeping the rope taut, and the buffer will then run down the cable C toward the tower A until it is checked by the stop F¹⁰, striking the lug F⁹. Unless the position of the stop F¹⁰ is changed the buffer will continue to run to the same point after each impact. When a sufficient amount of coal has been dumped at that point, the stop, which is secured in place by a set-screw F¹¹, is readjusted, and the buffer will stop nearer to or farther from the tower B, as may be desired.

In operation the dumping-car is arranged upon the track of the shaft-house derrick and also upon the track-cables C. The stock to be piled is then discharged from the car A³ into the dumping-car D, and the said dumping-car is then moving out upon the track-cables by means of the rope G until spring-actuated catch-lever E contacts with the buffer F, arranged at the proper point upon the track-cables. As soon as the lever E comes in contact with the buffer the spring E³ is compressed and the ends E² are disengaged from the bottom D⁴, and the said bottom then drops, discharging the ore upon the pile at the proper point. The direction of motion of the rope G is then reversed and the car returned to its original position, and as the car is drawn toward the shaft-house derrick the hinged bottom comes in contact with the curved or inclined buffer-block, thereby lifting and closing the bottom of the car, so that it is ready to receive another charge of material to be dumped.

It will thus be seen that we provide an exceedingly cheap, simple, and efficient construction of ore conveyer and piler, one which is nearly automatic and will thereby dispense with a considerable quantity of labor, and one which will avoid the use of any considerable quantity of rigging and one which can be quickly and easily removed when not required for use.

Having thus fully described our invention, what we claim as new, and desire to secure by Letters Patent of the United States, is—

1. A device of the kind described comprising a derrick and a tower, an elevated track connecting the derrick and tower, a car movable on the track, a buffer movable on the track, a plurality of rollers arranged on the sides of the buffer and adapted to engage the

upper and lower surfaces of the track, respectively, and means for holding the buffer in position.

2. A device of the kind described comprising an inclined track, a buffer, rollers carried on each side of the buffer and traveling on the track, rollers arranged below the first-mentioned rollers and engaging the under side of the track, a pulley arranged in the rear of the buffer, a cable passing over said pulley and connected at one end to the buffer, a weight attached to the lower end of the cable, a stop; and a lug on the cable engaging said stop and limiting the movement of the buffer in one direction.

3. In a device of the kind described, a car having a hinged bottom, a bifurcated catch-

lever pivoted to one end of the car, the lower hooked ends of said lever being adapted to engage the bottom of the car, the spiral spring, 20 the sleeve for containing said spring, and the cross-bar connecting the members of the lever and against which the spring bears, for the purpose specified.

4. In a device of the kind described, a buffer comprising an open frame having interior brace-beams and the guide-rollers arranged upon the sides in suitable loops or brackets, as specified.
